2 Sheets-Sheet 2

UNITED STATES PATENT OFFICE

FRANK E. LEAHY, OF YOUNGSTOWN, OHIO, ASSIGNOR TO THE YOUNGSTOWN SHEET AND TUBE COMPANY, OF YOUNGSTOWN, OHIO, A CORPORATION OF OHIO

FURNACE

Application filed June 9, 1930. Serial No. 459,971.

My invention relates more particularly to furnaces of the type used for box annealing or annealing sheets in packs.

In such furnaces as heretofore constructed it has been the usual practice to introduce the heating gases on one side of the charge, which may consist of the usual box holding the material to be annealed, a pack of sheets or the like, through a burner positioned near the bottom and to one side of the heating chamber so that the flame is projected upwardly and over the charge, then down the other side thereof, and finally under it to an outlet through which the waste gases can escape. The flame is thus caused to encircle the charge, causing hot spots at some portions thereof and cold spots at others as the flame cools down in its travel, with consequent unevenness in the annealing, so that it often becomes necessary to re-anneal the whole charge with resulting waste of fuel and labor as well as increased wear, tear and deterioration of the furnace itself.

A principal object of my invention, therefore, is to provide a novel form of furnace adapted for box annealing or the like by the use of which the charge may be evenly and uniformly heated throughout and the unsatisfactory conditions to which I have briefly referred thus entirely avoided. A further object of my invention is the provision of a furnace of this character in which the course of the heating gases in their traverse of the heating chamber may be so controlled that their heat is distributed evenly throughout the charge with resulting uniformity in the heating of all parts thereof; which is so constructed that it is possible for the operator to alter the course of the heating gases at will so as to increase the local heating of one part of the charge over another when such increase is required to eliminate cold spots or reduce the tendency to overheating with consequent creation of a hot spot at some point in the charge, and which is of simple design and construction and may be readily operated by workmen of the ability of those usually employed in the management of annealing furnaces.

My invention further comprehends gen-

eral improvement of the design and construction of furnaces of the general class of those to which it relates, as well as other objects and novel features hereinafter more particularly pointed out or which will be apparent to those skilled in the art from the following description of a furnace constructed in accordance with one embodiment of my invention and illustrated in the accompanying drawings, in which:

Fig. 1 is a top plan view of the furnace with the ends broken away into horizontal section on a plane somewhat below the level of the roof, and Fig. 2 is a staggered vertical transverse section through the furnace substantially on the line 2—2 in Fig. 1 looking in the direction of the arrows, like characters of reference being used to designate the same parts in both figures.

As shown, the furnace comprises longitudinally extending parallel side walls 1, a transversely extending rear wall 2 and a transversely extending front wall 3 provided with a door opening 4 which may be closed by the usual vertically slidable door 5 and through which the charge to be annealed may be introduced on a suitable truck running on the usual tracks 6—6 extending longitudinally of the furnace at its center and let into the hearth 7 forming the bottom of the heating chamber 8 which is closed at its top by the roof 9 extending between the side and end walls and desirably slightly transversely arched as shown in Fig. 2. The walls of the furnace are supported exteriorly by the usual buckstays 10 disposed at suitable intervals and may desirably be sheathed with metal 11.

For admitting the heating gases to the heating chamber I provide a suitable burner 12 adjacent each corner thereof and situated a little above the level of the hearth, each burner comprising suitable means for regulating the flow of air and fuel therethrough so that the temperature of the flame delivered by the burner into the furnace may be controlled.

Beneath the hearth of the furnace and extending longitudinally and substantially centrally thereof, is formed a flue 15 communicating with the interior of the furnace

through longitudinally spaced ports 16 and communicating through a transverse flue 17 with the stack 18; by means of this flue waste gases may be withdrawn from near the bottom of the chamber substantially uniformly along the hearth.

Disposed upon the hearth at laterally spaced intervals are longitudinally extending piers 20 adapted to receive and support the charge, generally designated as C, and which may be a box containing the material to be annealed, a pack of sheets or the like; these piers are transversely pierced at intervals by openings 21 through which the heating gases can circulate uniformly beneath the charge and thence into the ports 16 in the hearth.

At spaced intervals in the roof of the furnace and substantially centrally thereof I provide ports 22 which may be of any desired number and shape, although I prefer and have shown in the accompanying drawings three such ports equidistantly spaced along the center line of the roof and each of circular cross section.

For controlling the flow of gases from the furnace I also provide in association with the stack and the ports 22 which will, for convenience, be hereinafter termed the roof ports, dampers which may be of any form suitable to regulate the flow of gases through the passages which they respectively control. I may thus provide the stack 18 with a damper 24 hingedly supported adjacent the top of the stack and provided with a counterweight 25 and may in like manner provide each of the roof ports with a similar damper 26 supplied with a counterweight 27, and as the roof ports 22 are preferably each of smaller effective area than the stack, their dampers 26 will of course, and as shown, be correspondingly smaller than the stack damper 24, while the counterweights 25 and 27 are in each case sufficient to over-balance their respective dampers and thus urge the latter to open position unless prevented by suitable controlling means, such, for example, as those which I have shown in the accompanying drawings and which I shall now proceed to describe. However, while the said means are well adapted for the performance of their intended function, particularly when employed in connection with the hinged and counterweighted dampers to which I have referred, it will be understood that other forms of damper controlling means may be utilized if preferred either with dampers of that character or with dampers of other forms.

Thus, as shown each of the roof dampers 26 may be provided with an arm 26' on the opposite side of the damper hinge from that on which the counterweight is disposed, to which is connected a cable 30 extending generally transversely of the roof to a drum 31 supported on a longitudinally extending hor-

izontal shaft 32 journaled in brackets 33 secured to the buckstays or any other convenient point adjacent the side wall of the furnace. The drums are secured to the shaft as by set screws 34 so as to rotate therewith, and all of the cables but one are carried about their respective drums and the ends then secured thereto, so that as the shaft is rotated these cables will be either wound or unwound from their drums. One of the cables, however, for example 30', instead of having its end secured to its drum, is carried thereabout for one or more turns and thence downwardly to another drum 35 disposed on a shaft 36 journaled in pedestals 37 mounted on a platform 38 adjacent the side of the furnace or otherwise supported in any convenient way. This shaft extends at right angles to the shaft 32 and is provided with a crank 39 whereby it may be manually rotated, a locking screw 40 or other means for holding the shaft in any position of rotational adjustment being preferably provided.

Thus, when the shaft 39 is turned in such direction as to wind the cable 30' on the drum 35, the shaft 32 will be correspondingly rotated in a direction to wind the cables 30 on their drums 31 which it supports, thereby simultaneously pulling all of the dampers 26 down from the position shown in Fig. 2 in opposition to their respective counterweights and toward the roof ports which they respectively control. Likewise, when the crank is rotated in the other direction so as to unwind the cable 30' from the drum 35, the counterweights on the dampers are effective to rotate the shaft 32 in reverse direction with consequent simultaneous opening of all of the roof dampers.

The shaft 36 is also provided with another drum 41 from which a cable 42 extends upwardly over a sheave 43 on a shaft 44 extending parallel to shaft 32 and journaled in suitable brackets 45 carried by the buckstays and thence to the arm 24' of the stack damper, in such manner that the latter will be closed or opened in correspondence with the direction of rotation of the shaft 35, the respective diameters of the drums 35 and 41 being preferably so calculated and the other parts of the controlling mechanism preferably so arranged that when the roof dampers 26 are being opened, the stack damper 24 is being correspondingly closed and vice versa; thus, when the latter is in fully closed position the roof dampers are opened to permit unrestricted flow of gases through the roof ports and conversely, when the roof dampers are fully closed the stack damper is in fully opened position to permit unrestricted flow of gases through the stack, while in intermediate positions of the dampers the degree of restriction of the flow of gases through the stack is maintained roughly in inverse proportion to the degree of restriction of the

flow through the roof ports. Thus, assuming that the capacity of the stack is substantially equal to the total capacity of the roof ports, the total amount of waste gases flowing from the furnace is substantially constant regardless of the position of the various dampers, although it will be understood that the relative size or capacity of the stack and of the ports forms no part of my invention.

The operation of a furnace constructed substantially as just described is as follows: A charge C, such as an annealing box containing the material to be annealed, is disposed on the piers 20 with the aid of a charging truck which is then withdrawn and the door closed in the usual manner, a plurality of pyrometer thermo-couples T being preferably distributed at different points in the wall 15 of the box or in the charge itself and connected as by wires W to pyrometers (not shown) located outside the furnace to enable the temperature attained by various parts of the charge to be readily ascertained by the operator. Air and gas in suitable quantities are then admitted to the heating chamber through the burners 12, the combustion of the fuel producing the heating gases employed for heating the charge. As the temperature 20 within the furnace is raised, the heat of the various portions of the charge is shown by the pyrometers or other indicating devices connected to the pyrometer thermo-couples distributed about the charge, and thus it may 25 readily be determined which, if any, portion of the charge is receiving the proper amount of heat and which portions, if any, are receiving greater or less than the required amount. Such determination having been 30 made and assuming that the top of the charge is receiving too great an amount of heat in proportion to that received by the bottom of the charge, the dampers 24 and 26 are operated by means of the crank 39, or other suitable 35 means which may be provided for the purpose, in such manner that the flow of waste gases through the roof ports is restricted and that through the flue 17 is enhanced, thus causing a greater proportion of the heating 40 gases to flow adjacent the bottom of the charge, and restricting the flow of gases about the top thereof with corresponding regulation of the relative amounts of heat received by the different parts of the charge. Conversely, if the bottom of the charge is receiving 45 too great a proportion of the heat supplied to the furnace, this situation may be readily corrected by moving the dampers respectively in opposite directions from those just referred to, that is, by opening the roof dampers more widely to cause larger quantities of the heating gases to flow over the top of the charge so as to increase the temperature of the latter, while correspondingly 50 moving the stack damper to a position fur-

ther restricting the passage of gases through the stack and consequently decreasing the proportion of gas flowing adjacent and supplying heat to the bottom of the charge. Thus, by noting the temperature of the various parts of the charge from time to time and correspondingly regulating the roof port and stack dampers to properly direct the flow of the gases, a very even and uniform heating of the entire charge may be obtained even under conditions of operation, such as high winds causing excessive stack draft or the like, which are highly inimical thereto.

While I have referred more especially to a form of damper control means adapted for manual operation, it will be apparent to those skilled in the art that, if desired, the respective dampers may be operated by suitable automatic means, as for example, an electric motor arranged to drive the shaft 36, and which may be so interconnected with the heat indicating pyrometers, in a well-known manner, as to provide fully automatic operation of the dampers and uniform and efficient heating of the charge substantially without attention from plant operatives during the heating period.

While I have herein shown and described with considerable particularity a furnace constructed in accordance with one embodiment of my invention, it will nevertheless be understood that I do not thereby desire or intend to restrict myself specifically thereto, as numerous changes and modifications may be made in the form and arrangement of the various parts and in the manner of their association with each other, if desired, without departing from the spirit and scope of the invention as defined in the appended claims.

Having thus described my invention, I claim and desire to protect by Letters Patent of the United States:

1. A furnace of the class described comprising a heating chamber and a hearth disposed therebeneath, a flue extending from the hearth adapted to conduct waste gases from the lower part of said chamber, means for introducing heating gases into said chamber, means adapted to conduct waste gases from another part of said chamber, and interconnecting means for simultaneously and selectively controlling the flow of gases through both of said conducting means.

2. A furnace of the class described comprising a heating chamber, means for introducing heating gases thereinto, means for conducting waste gases from different parts thereof, dampers operative to control the passage of said waste gases through said conducting means, and means for simultaneously actuating said dampers in opposite directions with respect to the conducting means respectively controlled thereby.

3. A furnace of the class described com-

- prising a heating chamber, means for introducing heating gases thereinto, means for conducting waste gases therefrom, dampers respectively operative to control said conducting means, and means for simultaneously actuating said dampers in such manner that the relative proportional restriction of the flow of waste gases through one of said conducting means is maintained in substantially inverse ratio to the relative proportional restriction of said flow through other of said conducting means.
4. A furnace of the class described comprising walls, a hearth, and a roof enclosing a heating chamber, means for introducing heating gases into said chamber, a flue extending in and leading from the hearth adapted to conduct waste gases from the lower part of the chamber, said roof being provided with a plurality of spaced ports also respectively adapted to conduct waste gases from the upper part of the chamber, a damper operative to control the flow of gases through the flue, dampers respectively operative to control the flow of gases through said ports, and means interconnected with all of said dampers operable to move all of the port controlling dampers in one direction with respect to the ports and to contemporaneously move the flue controlling damper in the other direction with respect to the flue.

In witness whereof, I have hereunto set my hand this 6th day of June, 1930.

FRANK E. LEAHY.
